UNITED STATES PATENT OFFICE.

CLAYTON M. JONES, OF JAMESTOWN, NEW YORK.

RADIATOR.

1,280,041.

Specification of Letters Patent. Patented Sept. 24, 1918.

Application filed September 18, 1915. Serial No. 51,018.

To all whom it may concern:*

Be it known that I, CLAYTON M. JONES, a citizen of the United States, residing at the city of Jamestown, in the county of Chautauqua and State of New York, have invented certain new and useful Improvements in Radiators, of which the following, taken in connection with the accompanying drawings, is a specification.

- 10 10 The invention relates particularly to radiators for cooling the water in motor driven vehicles; and the object of the improvement is to provide a strong and durable alternating water way conformation of the core
- 15 15 construction of the radiator so that the air flues are strongly supported by said conformation of the sheet metal and provide a large cooling surface as the air circulates through the same; also to provide water ways which are unobstructed, that is, while alternating as to direction of flow, yet are of substantially the same volume in cross section throughout their length; and the invention consists in the novel features and
- 20 20 combinations hereinafter set forth and claimed.
- 25 25

In the drawings, Figure 1 is an elevation of the radiator of a motor car showing air flues therethrough. Fig. 2 is an end elevation 30 30 of a portion of the core of the radiator showing the construction and arrangement of the same. Fig. 3 is a perspective view of a portion of the sheet metal strips as stamped out for the air flues and water ways and attached to one another; and Fig. 4 is an opposite perspective view of a single sheet metal strip which forms one side of a water way. Fig. 5 is a sectional view at line X X in Fig. 2, and Fig. 6 is a sectional view at line Y Y in Fig. 2, showing the water way in cross section and the manner in which the sheet metal is joined to each end and bent to form the water ways. Fig. 7 is a crosswise sectional view of the portion of 40 40 the core shown in Fig. 2, showing the manner of centering or supporting the alternating forms upon one another in building up the core.

Like numerals of reference refer to corresponding parts in the several views.

The numeral 10 designates the radiator which is made the size and as great length as possible for cooling the water in the motor.

55 55 The core of the radiator is made up of nested water ways 11 and air flues or open

ended tubes 12 which are formed by means of bent up sheet metal strips 13 which are shaped by a suitable die in the alternating form shown so as to provide a practically unobstructed water way 11 therebetween, that is, one which has substantially the same volume in cross section throughout its length, though said water way is full of return bends. This angular shape gives 60 60 form to the air flues 12 and also forms the wedging seats for one pair of attached sheet metal strips 13 upon the adjacent pair.

Each of the sheet metal strips 13 which form the opposite sides of the water way 70 70 11 are bent up by the same die. This is quickly understood when it is noted that the sheets forming the water ways are made with similar alternating convex and concave bends, the concave or inner bend of each sheet 13 continuing in the convex or outer bend in the next turn of the water way, hence it is only necessary after forming one side strip 13 to shift the next sheet metal strip one bend of the die to form the strip 80 80 13 for the opposite side of the water way.

The strips 13 are shaped and fitted onto one another as follows: Each sheet is composed of alternate concave and convex bends separated by the horizontal portions 14 85 85 which form the top and bottom of the air flues 12, the V-shaped angular bends 15 for the convex outer sheet and 16 for the concave inner sheet forming the vertical sides and connecting said horizontal portions. 90 90 The convex outer sheet 15 is provided with shoulders 17 along the contact surfaces 18 and which fit within the opening in the concave portion formed by the spaced return bends or corrugations, thereby closing 95 95 the open vertical side of the opening 12 and forming a closed air flue with water circulating on all sides thereof as well as holding the parts firmly in line.

The guiding shoulders 17 provide a guiding limit for the flat converging contact surfaces 18 which bear against the similar shaped converging contact surfaces 18 and shoulders 17 of the adjacent pair of strips 13. It is apparent that the projecting shoulders 17 fitting closely within the inner walls of the opening 12 make the adjacent strips 13 self-centering upon one another and holds them firmly in position, making an exceedingly durable and rigid construction which 100 100 105 105 may be soldered together at the edges and on the shoulders 18.

The edges 19 of the strips 13 are preferably attached to one another by soldering to form a reinforcing fin of double thickness. The inner point 20 is rounded in order to aid in the smooth flow of the water through the water way 11 and widen the opening at this point. The water way 11 is proportioned as to size according to the amount of water which it is necessary to deliver from the reservoir 21 at the top into the reservoir 22 at the bottom of the radiator.

When in use, the water enters the water ways 11 through the openings 23 at the upper end and flows back and forth through the serpentine passages of the water ways, thereby providing an equal volume of water on all sides of the air tubes 12 so that the air may cool the water as quickly as possible. The water passes out of the openings 24 at the bottom of the radiator and from thence is returned to the motor cooled and ready for use.

The alternating return bend construction of the water ways with the self-centering shoulders so holds the strips 13 which form the water ways 11 that a small amount of solder only is necessary for holding said water ways firmly in position. It is recognized that the hotter the radiator becomes the greater the stress thereon from the expansion of the metal and the softening of the solder which tend to tear the joints apart thereby causing leaks and this stress is increased by the vibration of the car. The bracing construction of the alternating convex and concave water ways whereby the flow of the heated water through said water ways is in alternate directions so that the consequent heating of the metal and expansion of the same is neutralized, that is, the expansion is equalized by the alternating

flow in both directions and hence the strain on the joints is also equalized and the stress on the radiator core is reduced to the minimum.

It is apparent also that the soldered edges 19 abut upon one another in the adjacent water tubes at each end 25 of the horizontal portions. This arrangement of the core also greatly strengthens and braces the entire construction of the water tubes.

I claim as new:

In a radiator for motor cars, metal sheets each bent to have pairs of parallel horizontal parts, alternately connected at their ends by approximately V-shaped parts, said pairs of horizontal parts being alternately held in relatively widely and closely spaced relation by said V-shaped parts, the outer ends of each of the sides of the V-shaped parts of the widely spaced horizontal parts having inwardly extending depressed parts forming abrupt shoulders at the inner ends of said depressed parts, said sheets being arranged in pairs with the closely spaced horizontal parts extending into the widely spaced horizontal parts to form water passages in conjunction therewith, the V-shaped ends of the widely spaced horizontal parts of adjacent plates pointing in opposite directions and having their depressed parts completely seating one within the other, the shoulders of said last named V-shaped ends engaging the inner faces of the sides of the adjacent closely spaced horizontal parts of the adjacent plates to form substantially Z-shaped joints.

In testimony whereof I have affixed my signature in the presence of two witnesses.

CLAYTON M. JONES.
